US00D637102S

(12) **United States Design Patent**
Papadimitriou

(10) **Patent No.:** **US D637,102 S**
(45) **Date of Patent:** **** May 3, 2011**

(54) **RING**

(75) Inventor: **Costantino Papadimitriou**, Milan (IT)

(73) Assignee: **De Beers Centenary AG**, Lucerne (CH)

(**) Term: **14 Years**

(21) Appl. No.: **29/377,682**

(22) Filed: **Oct. 25, 2010**

(30) **Foreign Application Priority Data**

Apr. 25, 2010 (EP) 001699760
(51) **LOC (9) CL.** **11-01**
(52) **U.S. CL.** **D11/35**
(58) **Field of Classification Search** D11/26-39;
63/15.1-15.4, 15.45, 15.5, 15.6, 15.65, 15.7,
63/26-27

See application file for complete search history.
